SEBERN J. WEVER, OF SHELLER, ILLINOIS.

TABLE-SPREAD SUPPORT.

No. 809,546.

Specification of Letters Patent.

Patented Jan. 9, 1906.

Application filed August 23, 1905. Serial No. 275,469.

To all whom it may concern:

Be it known that I, SEBERN J. WEVER, a citizen of the United States, residing at Sheller, in the county of Jefferson and State of Illinois, have invented certain new and useful Improvements in Table-Spread Supports, of which the following is a specification.

This invention embodies an improved support for use upon dining-tables particularly and designed to support a cover or cloth over the dishes on the table.

The spread-supports heretofore devised have been found impracticable to a certain extent because of the expensive structures used and, further, on account of the fact that the same are not affixed to the table, but can be readily displaced therefrom in placing the spread in position or removing the same, giving rise to likelihood of breaking of the dishes, and possessing other disadvantages.

For a full description of the invention and the merits thereof and also to acquire a knowledge of the details of construction of the means for effecting the result reference is to be had to the following description and accompanying drawings, in which—

Figure 1 is a perspective view showing the invention applied to a table. Fig. 2 is a vertical section through the table, showing one of the supports comprising the invention. Fig. 3 is a detail perspective view of one of the supports comprising the invention.

Corresponding and like parts are referred to in the following description and indicated in all the views of the drawings by the same reference characters.

In the actual adaptation of the invention it is designed that two supports be used for the ordinary dining-table in order to hold the spread above the same for the purpose hereinbefore set forth. Each of these supports comprises a frame 1 of curved or somewhat V form, said frame 1 embodying downwardly-extending arms 2. The frame 1 is preferably of integral formation, and in order that the same may be of the cheapest practical form it is preferred that it be made of a single length of spring-wire bent upon itself between its ends to form a plurality of coils 3, which constitute a spring. The arms 2 of the frame 1 are coiled at a point between the ends thereof to form loops 4; which also tend to give a spring action to the arms, resisting the spread thereof. The supporting-frame 1

is adapted to be secured to the table (indicated at 5) and when in position thereon will be rigid for all purposes, so that the spread 6 (shown in dotted lines) may be readily thrown upon the table or removed therefrom without displacing the frames 1. The arms 2 have hooks 7 at the lower extremities thereof, and these hooks are adapted to engage opposite edge portions of the table to positively hold the frame 1 in position thereon, the spring action of the parts 3 and 4 being such as to cause the necessary engagement of the hooks 7, as above described.

In order that the frame 1 may be held in an upright position on the table, the hooks 7 have the terminal portions thereof extending laterally to form the extensions 8, projecting in opposite directions, and these extensions by positive engagement with the under side of the table 5 brace the frame 1 and prevent it from tilting toward one side or the other.

Having thus described the invention, what is claimed as new is—

1. A table-spread support comprising a frame embodying integral spring-arms, hooks carried by the said arms for engagement with a table and so connected with the arms as to be held in such engagement by the spring action thereof, and members carried by the hooks for holding the frame in an upright position.

2. A table-spread support comprising a frame composed of oppositely-extending arms, hooks at the ends of said arms for engagement with a table to attach the frame thereto, and extensions projecting laterally from the hooks for coöperation with the object engaged thereby to brace the frame and hold it in an upright position when affixed to the table.

3. A table-spread support comprising a frame composed of oppositely-extending arms, and hooks at the ends of said arms for engagement with a table to attach the frame thereto, each hook being extended laterally to form a brace extension for holding the frame in an upright position, the brace extensions of the hooks projecting in opposite directions.

4. As a new article of manufacture, a table-spread support comprising an integral frame embodying oppositely-extending curved arms made from a single length of spring-wire, the wire being coiled upon itself

at a point between its ends to form a spring for the arms, each arm being coiled to form a spring-loop, the lower extremities of each arm being formed with an integral hook, the 5 terminals of each hook being extended laterally in opposite directions to form brace members for the purpose specified.

In testimony whereof I affix my signature in presence of two witnesses.
